CUTLERY RACK OR SIMILAR ARTICLE

Dean J. Case, Little Valley, N. Y., assignor to Kin-folks Incorporated, Little Valley, N. Y., a corporation of New York

Application June 4, 1949, Serial No. 3,054

Term of patent 7 years

(Cl. D44—29)

To all whom it may concern:

Be it known that I, Dean J. Case, a citizen of the United States, residing at Little Valley, in the county of Cattaraugus and State of New York, have invented a new, original, and ornamental Design for a Cutlery Rack or Similar Article, of which the following is a specification, reference being had to the accompanying drawing, forming part thereof; and in which

Fig. 1 is a plan view of a cutlery rack or similar article, showing my new design;

Fig. 2 is a side elevational view; and

Fig. 3 is an end view.

I claim:

The ornamental design for a cutlery rack or similar article, substantially as shown.

DEAN J. CASE.
